(57) **CLAIM**

We claim the ornamental design for a fan module, as shown and described.

DESCRIPTION

FIG. 1 is a front perspective view of the fan module comprising the present invention;

FIG. 2 is an enlarged front view thereof;

FIG. 3 is an enlarged left side view thereof;

FIG. 4 is an enlarged top view thereof; and,

FIG. 5 is an enlarged bottom view thereof.

The broken line showing of a plurality of fan modules is included for the purpose of illustrating environmental structure and forms no part of the claimed design.
